UNITED STATES PATENT OFFICE

JOHN T. HAWKINS, OF TAUNTON, MASSACHUSETTS.

PERFECTING PRINTING-PRESS.

SPECIFICATION forming part of Letters Patent No. 257,581, dated May 9, 1882.

Application filed April 18, 1881. (No model.)

To all whom it may concern:

Be it known that I, JOHN T. HAWKINS, of Taunton, in the county of Bristol and State of Massachusetts, have invented a new and useful Improvement in Perfecting Printing-Presses, which improvement is fully set forth and illustrated in the following specification and accompanying drawings.

The object of this invention is to provide a rapid and correct means of printing newspapers and other work from flat forms, and to print both sides of the sheet at one operation, either from a continuous web or roll of paper or from separate sheets, as may be desired.

The invention consists broadly in constructing a press having two impression-cylinders, one in advance of the other, and a single type-bed carrying two forms, and wherein the first cylinder receives each sheet at its top and delivers it from its top, head first, to the bottom of the second cylinder, which there receives the sheet and delivers it from its top tail first, the various adjuncts and details forming parts of the invention being particularly hereinafter described and specifically set forth in the claims.

The invention as illustrated in the several figures of the accompanying drawings will now be described as follows:

Figure 1 is a side elevation, Fig. 2 is a rear elevation, and Fig. 3 is a plan, of the machine as designed to be fed with separate sheets from an ordinary feed-board and to print and deliver the same flat upon an ordinary fly-board. Fig. 4 shows in two views the impression-cylinder which prints the last side of the sheet, and Fig. 5 the impression-cylinder which prints the first side, both cylinders enlarged, and exhibiting details of construction omitted in Figs. 1, 2, 3, 10, and 11 for the sake of clearness of illustration. Fig. 6 illustrates in two views the grippers belonging to the first cylinder, and Fig. 7 illustrates, also in two views, the sheet-lifter fingers belonging to the same cylinder. Fig. 8 illustrates the distortion of the gripper-edge of the sheet caused by the old method of clamping the sheet upon the tympan over and between the sheet-lifter fingers by spacing the grippers between the sheet-lifter fingers. Fig. 9 shows the smooth and undisturbed condition of the said

gripper-edge of the sheet when held upon the sheet-lifter fingers by the grippers, as provided for in this invention. Fig. 10 is a side elevation, and Fig. 11 a plan, of the machine as designed to print from a continuous web or roll of paper and to deliver the printed matter in separate sheets to a folding-machine which may be attached thereto. Fig. 12 illustrates in two detached views (one in section) the apparatus for separating the web of paper into sheets as it is fed from the roll and delivered to the grippers of the first-impression cylinder, which apparatus is shown attached in position in the preceding Figures, 10 and 11. Fig. 13 illustrates certain details of the folding apparatus, hereinafter described. In these several figures of the drawings all that relates to the opening and closing of the grippers, the feed-guides, and the inking apparatus, except the arrangement and positions of the form-rollers, is omitted as not essential to the invention, several of the well-known plans of each of these being applicable to this invention. In Fig. 2 the feed-board is omitted. In Fig. 3 both the feed-board and fly-board are omitted for the sake of more clearly illustrating other parts of the machine.

In the said figures, the letter A indicates the side frames of the machine; B, the first-impression cylinder; B', the second-impression cylinder; B², the type-bed; T, the type or form for printing the first side of the sheet, and T' the type or form for printing the second side of the sheet, the two forms being placed end to end in the direction of the length of the press, and the impression-cylinders B and B' being so placed as to give the bed B² the least traverse or stroke consistent with the proper inking of the form and the delivery of the sheets. R indicates the inking-rollers for the first-side, and R' the inking-rollers for the second-side, impression, the ink-fountains and other parts of the inking apparatus being omitted.

C indicates the feed-board, and C' the fly-board, for that form of the press to which separate sheets are fed by hand.

The crank G is secured to the shaft G', and is driven by a gear-wheel, G², also secured to the shaft G'. Said gear-wheel G² is itself driven by a pinion, G³, secured to a shaft, G⁴,

journaled in suitable bearings in the frames A and carrying the two fly-wheel pulleys G⁵. To the crank G is attached the crank-pin c, to which one end of the connecting-rod c' is jointed, 5 the other end of said rod being jointed to the rolling pinion P.

The stationary rack E is secured to the bed-piece or roller-ways of the press, and a corresponding rack, E', is secured to the under 10 side of the bed B², between which racks and engaging both said rolling pinion P revolves and travels.

Upon the shafts s s, which, with the shaft P', are journaled in the carriage or roller-frame K, 15 is a series of rollers, E². Said rollers run in the roller-ways R² and support the bed B² by corresponding roller-ways, R³, in the underside of the bed B². The object of the last-described arrangement is to give to the bed B² twice the 20 rectilinear motion imparted by the crank G to the carriage K, and thus to avoid the use of too long a crank, while still imparting to the reciprocating parts the easy reversal at the ends of the stroke peculiar to the crank motion.

25 The two impression-cylinders B and B' are geared directly to and are driven directly by the bed B² by means of a rack, R⁴, secured to the upper side of the bed B² and corresponding gear-wheels, R⁵ R⁶, secured to the cylinders 30 B and B', which engage the rack R⁴, the cylinders B and B', rotating in either direction as actuated by the bed B². The impression-cylinders B and B' are so proportioned that they each make a greater rotation than one complete revolution in each direction for the purpose of obtaining a minimum diameter of cylinder—in the case of the cylinder B to carry the head of the sheet after its first complete revolution far enough down the inclined 35 bridge-fingers f' to reach the grippers of the second cylinder, B', and in the case of the cylinder B' to carry the tail of the sheet m sufficiently high above the form to allow of its being passed to and delivered upon the fly-fingers 40 f at the commencement of the cylinder's retrograde or non-printing rotation, as hereinafter more fully explained.

The shaft D runs parallel with the side frame, A, at the right hand in Fig. 2, in suitable 45 bearings attached to the said frame, and is driven from the shaft G' by a pair of miter-wheels, D³ and D². On the shaft D are secured two cams, D³ and D⁴, and the sliding bars D⁵ and D⁶ are held in their places by two collars, D⁷ and 50 D⁸, secured to the shaft D. The sliding bars D⁵ and D⁶ are slotted to embrace the shaft D, and carry in their upper ends the rollers D⁹ and D¹⁰, which engage the grooves in the cams D³ and D⁴. The sliding bars D⁵ and D⁶ carry 55 also on their lower ends short racks, the backs of which run against the two friction or idler rollers D¹¹ and D¹², which run upon studs secured to the frames A for the purpose of keeping said racks in gear with two sector-gears, D¹³ and D¹⁴, secured to the eccentric rock-shafts D¹⁵ and D¹⁶. The eccentric parts at 60 each end of the rock-shafts D¹⁵ and D¹⁶ are

journaled in the cylinder-journal side rods, D¹⁷ and D¹⁸, and the cylinders B and B' are journaled in the upper ends of the side rods, D¹⁷ 70 and D¹⁸.

The effect of the operation of the parts last described, from D to D¹⁸, is to both raise and lower the impression-cylinders B and B' at the proper times, the form and position respectively given to the cams D³ and D⁴ upon the shaft D being such as to lower and retain in that position the cylinders while making the impressions, and to raise them and hold them clear of the forms during the retrograde or 80 non-printing stroke of its corresponding form, but not sufficient to take them out of gear with the rack R⁴. As the bed B² prints the first side of the sheet while it runs in one direction and the second side while it runs in the opposite direction, one cylinder remains elevated 85 while the other is depressed, or nearly so.

With the above-described positions and proportions of parts the inking-rollers R will run partly over the form T' belonging to the cylinder B', and the rollers R' partly over the form T belonging to the cylinder B; but in order thus to avoid the inking-rollers belonging to one form coming in contact with the other form while the latter runs partly under each 90 set of said rollers, there are secured to the upper side of the bed B² two sets of roller-bearers, B³ and B⁴, each pair of bearers being set out of line with the others; and upon the ends of the inking-rollers R are secured the roller-wheels B⁵, slightly larger in diameter than said rollers, and so placed upon them as to come in contact with and run only upon the bearers B⁴ of that part of the bed B² which carries the form T' for printing the second side; and, conversely, there are similar roller-wheels, B⁶, on the rollers R', so placed as to run only on the bearers B³ on that part of the bed B² which carries the form T for printing the first side. In this way each set of inking-rollers is caused 95 to run from end to end of its own form in contact therewith, but does not touch any part of the other form. Without this arrangement one pair of rollers would run partly upon and reverse upon the opposite form, which would 100 interfere with the proper distribution of the ink on the forms and fill up the fine lines in the form at the point of reversal. Two racks, E⁴, are secured to the under side of the bed B², 105 engaging which are the spur-wheels E⁶, running upon studs E⁷, secured to the frames A. Two long heavy weights, E⁸, run upon grooved rollers E⁹, and a rib on the lower side of each weight runs in the respective grooves of each 110 of said rollers, which ribs serve as guides for their respective weights. The grooved rollers E⁹ run upon the shafts s' s', journaled in the frames A, and the roller-ways R². Upon the upper sides of the weights E⁸ are secured racks E⁵, also engaging the wheels E⁶. The weights 115 E⁸ are cast with pockets E¹⁰, for the purpose of loading said weights as may be desired.

The office served by the parts described as s' and E⁴ to E¹⁰ is to equilibrate the respective

momenta of the reciprocating bed B², with its type-forms, the carriage or roller-frame K, with its rollers, and the efforts or momenta exerted by the rotary cylinders to propel the bed B², 5 all during the last half of either stroke of the bed, and thus to avoid all tendency to impart vibrations to the machine as a whole through the inertia of the reciprocating parts when run at high speeds, the weights E⁸ having motion 10 at all times in a direction contrary to that of the other main reciprocating parts.

It is designed to so load the pockets E¹⁰ of the weights E⁸ for any weight of form used that their combined momenta or total momentum 15 shall equal the total horizontal momentum of all the otherwise unbalanced reciprocating parts moving in the opposite direction to said weights.

The vertical and horizontal momenta of the 20 crank G and connecting-rod c' are equilibrated by a counter-weight (not shown) placed in the wheel G² and set in opposition to the crank G.

Through the above-described systems of equilibrating the several momenta of the moving parts the machine may be run at high 25 speeds without vibration or tendency to move the machine as a whole.

The bridge or stripper fingers f' strip the sheet head first from the cylinder B, when the 30 sheet released by the grippers K' is lifted upon said strippers by the sheet-lifter fingers L, and down which strippers the head of the sheet passes to meet the grippers of the cylinder B', as will be hereinafter more fully described.

35 On the shaft D is secured a cam, F, engaging a roller, F', attached to a vertically-sliding bar, F², which at its lower end embraces the shaft D, and at its upper end carries a short rack, F⁶, held into gear with a sector-gear, F³, by the 40 idler-roller F⁴, running upon a stud in the frames A. The sliding bar F² is held in place at its lower end by the collar F⁵, secured to the shaft D. On the upper end of the sliding bar F² are placed weights W, which may be varied at pleasure, but sufficient to keep the 45 roller F' in the cam F when the sheet is on the fly-fingers f. The weight W requires to be varied for different sizes of sheets or speeds of press and the consequent variation in the resistance offered by the air to the passage of the sheet through it. The fly-fingers f and the sector-gear F³ are secured to a rock-shaft, f², journaled in the frames A.

50 All the parts described as f, f², W, and F to F⁵, inclusive, operate to deliver the sheet from the second cylinder, B', during its retrograde or non-printing rotation, and the cam F is so formed, proportioned, and angularly set upon the shaft D as to cause the fly-fingers f, 55 through the connections already described, to commence to move over to the fly-board c' when the whole of the sheet has passed upon said fingers. The fingers f will be away from the cylinder B' when the tail m of the sheet passes by the place occupied by the points of said fingers while at rest upon the rod f³ on

the direct or printing rotation of the cylinder B'. This position of said fingers will therefore allow the tail of the sheet elevated upon the sheet-supporting fingers o⁴, as will be 70 hereinafter more fully explained, to pass unobstructed by said fingers. The cam F is so placed, however, as to bring the fingers F to rest upon the rod f³ by the time the cylinder B' commences its retrograde or non-printing rotation, and said fingers are so placed as to cause their points to just clear the tympan upon the cylinder B' sufficiently 75 for the sheet to pass between them and the cylinder or its thin strip of steel o, Fig. 4, on 80 the direct or printing rotation. The tail m of the sheet elevated upon the sheet-supporting fingers o⁴, as shown in Fig. 4, will thus pass upon the fingers f and be stripped by them from the cylinder B' during the retrograde or 85 non-printing rotation of said cylinder.

The details shown in Fig. 4 will now be described as follows:

Fig. 4 illustrates in two views a side and an end elevation, enlarged, of the cylinder B' and certain details omitted from the other figures for the sake of clearness of illustration. In said figure the cylinder-grippers K' are operated to open and close at the proper time in any of the usual ways. In the end elevation, 90 m indicates the tail of the sheet, and o a very thin strip of steel extending across the cylinder B' and tightly stretched in contact with the usual blanket or tympan which covers said cylinder. The said strip o is thus stretched by 95 means of the adjustable slotted clamps o', which may be secured in any position in the circumference of the cylinder B' to suit different lengths of sheet by the screws o² and screw-holes o³. The strip of steel o is riveted to the 100 clamps o', and the latter fit into grooves, one at each end of the cylinder B', next to the cylinder-bearers B³. These grooves are beveled on their inner sides, as shown, for the purpose of tightly stretching the steel strip o 105 in contact with the blanket or tympan, all the parts o' and o² being below the impression-surface of the cylinder. The thin strip o has formed on one of its edges, toward the tail of the sheet m, a series of stationary sheet-supporting fingers, o⁴, curved up slightly from the cylinder-surface. The strip o, with its sheet-supporting fingers o⁴, is so placed (depending upon the length of sheet) that the tail m shall lie upon the slightly-raised fingers o⁴, and the 110 strip o and fingers o⁴ are so placed that only the points of the fingers o⁴ remain under the tail m of the sheet, on which there is nearly always an unprinted margin. All these said parts will therefore clear those parts which 115 make the impression, and as such parts are required to be only "type-high" upon the bed, (the chase, furniture, &c., being on a lower plane,) the strip o and fingers o⁴ can come in contact with no obstructions in passing through the 120 impression. The object in keeping the tail m of the sheet slightly raised by the fingers o⁴ is

to insure the entrance of the sheet upon the points of the fingers f as the cylinder B' commences its retrograde or non-printing rotation.

A small shaft, j^2 , is supported in slotted bearings in the frames A , in order to allow it to rise and fall with the cylinder B' . Said shaft carries two or more pressure rollers or wheels, j^3 , bearing by their own weight only upon the cylinder B' , and adjusted on the shaft j^2 so as to run upon the unprinted margins of the sheet. A similar shaft, j , Figs. 1 and 2, carries two or more similar rollers or wheels, j' , bearing upon the cylinder B , and running in similar slotted bearings in the frames A . Two levers, j^{10} , are pivoted, each at one end, to the frames A by the pivots j^{11} , their central parts resting upon the tops of the cylinder side rods D^{17} . The extended journals of the shaft j rest upon the free ends of the levers j^{10} . The office of the pressure-rollers j' and j^3 is to cause friction between the cylinder-tympana and the sheets, and thereby to insure the passage of the sheets fully upon the fingers f and f' . In the case of the cylinder B' , Figs. 1 and 2, the sheet is required to pass its whole length upon the fingers f , and the rollers j^3 may remain in contact with the cylinder or the sheet upon it during the whole of the retrograde or non-printing rotation of the cylinder, the journals of the shaft j^2 resting in the bottoms of their slotted bearings when the cylinder is depressed and printing. In the case of the cylinder B the sheets run down the fingers f' only during the last part of the direct or printing rotation of the cylinder, a portion of the tail end of the sheet still remaining upon the cylinder at the termination of its direct rotation. At this time, by the action of raising the cylinder B to clear the form for the retrograde rotation, the lever j^{10} is raised by the cylinder side rod D^{17} , so as to lift the shaft j , and with it the rollers j' , from the surface of the cylinder, (or from the sheet upon it,) to allow the remainder of the sheet to be withdrawn from the cylinder B by the grippers of the cylinder B' without resistance from the rollers j' , which would hold the sheet in contact with the cylinder B , then reversed and running in the wrong direction for the delivery of the sheet, if said rollers were to remain in contact with the sheet and press it against the retrograding or retreating cylinder.

In Figs. 5, 6, and 7 the grippers and the sheet-lifter fingers for the cylinder B are indicated respectively by the letters K' and L . The said lifter-fingers are thin strips of steel slotted to embrace the tongues of said grippers, except at the ends. The inner or fixed ends of the lifter-fingers L are held in a slotted shank, L^2 , and project a short distance into a corresponding narrow groove in the rod L' , as shown at L^4 , Fig. 7, and thus act as a feather or key to prevent the shank L^2 from rotating upon the rod or shaft L' . The shank L^2 has an easy sliding fit upon the rod L' , so that in making lateral adjustments of the grippers K' upon

said rod the fingers L may accompany them without other adjustments, the slots in said fingers preventing any lateral motion in them while in operation by reason of the tongues of the grippers acting in and through said slots as guides for said fingers. The rod L is prevented from rotating by a small arm, L^5 , secured to it at one of its ends and held in place by a pin or screw, L^6 , by removing which the rod L' , with its fingers L , may be rotated away from the gripper-edge of the cylinder B when the grippers K' are opened for the purpose of access to the tympan or other cylinder-covering. The free ends of the grippers K' fall upon the unslotted portion of the fingers L when the grippers are closed, the fingers then lying upon the tympan, and thus the sheet is clamped between the upper sides of the fingers L and the under sides of the grippers K' . The hubs of the grippers K' are wider than the tongues, and the fingers L have the same width as the hubs of said grippers at each side. Upon the hubs of the grippers K' are formed cam-shaped projections K^2 , and the narrow sides of the fingers L lie upon the hubs of the grippers K' . As said grippers are opened by the usual mechanism (not shown) the cams K^2 cause the fingers L to rise by the springing of the fingers, carrying with them the gripper-edge or head of the sheet resting upon them. By the time the grippers K' are wide open, as shown in section in Fig. 5, the fingers L are again lowered to rest upon the cylinder B . When the grippers K' are again closed to seize the sheet the fingers L are again lifted during that part of the cylinder's retrograde or non-printing rotation just preceding the seizing of the sheet, but resume their place upon the tympan before the grippers K' close upon the sheet inserted between the grippers and said fingers.

In Fig. 8 is illustrated in section the edges of cylinder-grippers with the lifter-fingers spaced between the grippers, the sheet being shown under the grippers and over the lifter-fingers, as practiced in the older methods. The objection to such method is, as clearly seen in said figure, that the sheet is forced into a corrugated or distorted form at the gripper-edge, thus interfering with accurate and certain lateral register. Fig. 9, however, illustrates the sheet in a straight line at its gripper-edge, as is the case when clamped directly on top of the fingers L , as provided for in Figs. 5, 6, and 7, the object of which provision is fully carried out by said means and the said tendency to distortion of sheet and inaccuracy of lateral register due to the old arrangement entirely obviated.

The following is a description of certain details illustrated in Figs. 10, 11, 12, and 13, Figs. 10 and 11 being general views, Fig. 12 showing details of the web-cutting apparatus, and Fig. 13 details of the folding apparatus.

The shaft D has a continuation, d , supported at its end in a suitable bracket or bearing, d' , attached to the frame A . The vertical shaft

d^2 is similarly supported, and receives motion from the shaft d by means of the bevel-gears d^3 and d^4 . A horizontal shaft, d^5 , journaled in the frames A, receives motion from the shaft 5 d^2 by means of the bevel-gears d^6 and d^7 . The shaft d^5 carries on the inside of the frames A a spur-gear, d^8 , engaging a similar spur-gear, d^{10} , upon a similar shaft, d^9 , parallel with the shaft d^5 , and similarly journaled in the frames 10 A. The shaft d^5 carries a cylinder, d^{11} , with a groove or slot, d^{12} , parallel with its axis, and a series of shallow circumferential grooves, d^{13} , into which the points of a series of stripper-fingers, d^{14} , enter. The shaft d^8 carries a cylinder, d^{15} , Fig. 12, which has secured therein a serrated knife, d^{16} , parallel with its axis, and projecting beyond its periphery a sufficient distance, and so situated with reference to the groove d^{12} in the cylinder d^{11} and the gears 15 d^9 and d^{10} as to enter the groove d^{12} at every revolution of the cylinders d^{11} and d^{15} and cut the web of paper p running from the roll p' into sheets of the proper length. The roll p' is carried in the brackets p^2 , extending from 20 the frames A. A leading-roller, p^3 , is carried in similar brackets, p^4 , projecting from the frames A. A pressure or feeding roller, p^5 , is journaled in the frames A, covered with a yielding and frictional substance—as felt, cloth, or 25 rubber—and adjusted to press upon the periphery of the cylinder d^{11} .

The shaft j^4 is journaled in slotted bearings in the frames A, and carries two or more pressure-rollers, j^5 . A similar and parallel shaft, 30 j^6 , carrying similar rollers, j^7 , is also journaled in the frames A. A similar shaft, j^8 , parallel with the shaft j^6 , carries rollers j^9 . The shaft j^6 is driven from the pulley b on the shaft d^5 by the belt b' , and the shaft j^8 by tapes or belts 35 b^2 running from the rollers j^7 to the rollers j^9 , these rollers acting as pulleys. Two levers, j^{10} , are pivoted to the frames A by the pivots j^{11} , their longer arms resting upon the tops of the side rods, D^{17} , and under the lugs j^{12} , projecting inwardly from the side rods D^{17} . The 40 extremities of the longer arms of the levers j^{10} operate to raise and lower the shaft j with its rollers j' , as already explained in the description of Figs. 1 and 3. The journals of the 45 shaft j^4 rest upon the extremities of the shorter arms of the levers j^{10} , by which means the shaft j^4 and its rollers are raised and lowered at the proper times by the raising and lowering of the side rods D^{17} , the shaft j^4 being up 50 when the shaft j is down. The shafts j^8 and j^9 , with the tapes or belts b^2 , serve to convey the web p , before being separated by the knife d^{16} , to and between the rollers j^7 , or between their tapes or belts and the pressure-rollers 55 j^5 , which latter convey the sheet to the grippers of the cylinder B after the knife d^{16} has separated it from the web p . The rollers j^5 being lifted from the sheet by the depression of the side rods D^{17} at the time the grippers of 60 the cylinder B seize the leading edge of the sheet, the severed sheet is then carried by the cylinder B at its own velocity without obstruc-

tion from the rollers j^5 . The web p runs under the feeding-roller p^5 , between it and the cylinder d^{11} , over the top of said cylinder, and between it and the cylinder d^{15} , the circumferences of which cylinders are each exactly equal to the length of the sheet to be printed. A pair of levers, g , are secured to the rock-shaft g^2 , journaled in the frames A, and carrying a 70 friction-brake, g^3 , pivoted to the lower ends of the levers g , and pressing against the roll p' by means of the lever-arm g' , secured to the outer end of the rock-shaft g^2 , carrying the adjustable weight W' . The object of these 75 last-described parts is obviously to prevent the too rapid rotation of the roll of paper p' .

The folding attachment or apparatus is in detail as below described.

A vertical shaft, h , driven from the shaft G^4 80 by the bevel-gears h^1 h^2 , carries on its upper end a pulley, h^3 , which, through the belt h^4 and pulley h^5 , imparts motion to one of a pair of vertical rollers, h^6 , for making the first fold in the printed sheet, the whole being carried in 85 a suitable frame-work or housing built upon or forming extensions of the frame A.

The remainder of the apparatus for making the succeeding folds and delivering the folded sheets is omitted as not essential to this invention, and this part of the folding operation may 90 be performed in many well-known ways, depending upon the number, location, and order of succession of the folds to be made.

To the rock-shaft f^2 is secured a folding-blade, f^4 , in common with and forming one of the series of fly-fingers f . The sheet-stop f^5 limits the passage of the sheet down the fingers f and prevents it from dropping farther down upon said fingers during the oscillation 100 of the fly (composed of said fingers and the folding-blade f^4) from its position of rest upon the rod f^3 over to the folding-rollers h^6 , to which it delivers the sheet. The cam F in this arrangement is a closed or box cam similar to the cams D^3 and D^4 , the rollers upon the sliding bar F^2 carrying it both up and down without the instrumentality of a weight, W , such as is shown in Fig. 1. Two of the fingers f adjoining the folding-blade f^4 are placed far enough from the blade f^4 to permit of the folding-rollers h^6 entering about to the depth of their semi-diameters between said fingers, the blade f^4 then passing between the rollers h^6 to 105 crease and divide the sheet between them for the first fold, as shown in Fig. 13, in which the folding-rollers h^6 and fly-fingers f are illustrated in transverse section with said fingers in position for delivering the sheet to the rollers, the form and position of the sheet at the 110 time of entering said rollers being also shown.

In presses of small dimensions built upon the above-described principle sufficient space 115 cannot be had under the fingers f for an ink-fountain, distributing-rollers, &c. In such cases the whole inking apparatus, including the form-rollers R, may be placed at the back of the cylinder B, under the feed-board C, Fig. 1, or under the fingers d^{14} , Fig. 10, where there is am-

ple room for such purpose, in which case the arrangement of the bearers B^3 and B^4 may be dispensed with, the form belonging to one cylinder in such an arrangement not running under the form-rollers belonging to the other form.

The complete operation of this invention is as follows: First, for printing from sheets separately fed from a feed-board. The sheet fed from the feed-board to the usual guides is taken thence by the grippers K' of the cylinder B just as said cylinder comes practically to rest by reason of the crank G having reached its "dead - center" farthest to the right, Figs. 1 and 10. Correct register is thus assured, as all the parts connected with the sheet are in a state of least motion. The crank G now commences to rotate in the direction of the arrows, Figs. 1 and 2, and to move the bed B^2 upon its forward or printing stroke for the cylinder B . The cam D^3 , through its connections already described, having at this point caused the cylinder B to descend into position to make the impression, the cam D^4 , through its connections, simultaneously raises the cylinder B' to clear the form and the bed B^2 causes the cylinders B and B' both to rotate in the same direction. The cylinder B' , at the commencement of the stroke now described, having just completed the printing of the second side of the preceding sheet, now performs its retrograde rotation during this passage of the crank G from its right to its left hand center, and delivers the preceding sheet upon the fingers f , and also brings its grippers at the termination of this retrograde rotation into position at the lower ends of the fingers f' to seize the advancing edge of the sheet coming from the cylinder B . During this same passage of the crank G or stroke of the bed B^2 the cylinder B prints the first side of the sheet, and at the completion of its first complete revolution the grippers K' are opened. The lifter-fingers L then raise the advancing edge of the sheet upon the upper points of the fingers f' , down which it passes by the performance of the last fractional part of a revolution of the cylinder B , (said sheet being driven by the pressure of the rollers j' , at this time resting upon it,) the head of the sheet reaching the bottom of the fingers f' just as the grippers of the cylinder B' arrive in place to grasp it. At this time all these parts have come to a state of minimum motion by reason of the crank G having arrived upon its dead-center at the left, Figs. 1 and 10. Thus the sheet is seized a second time under conditions insuring correct register upon the second cylinder, B' , the highest speed attainable by the machine as a whole in no wise interfering with said register. At this point the cylinder B is raised to clear the form and the cylinder B' depressed to make its impression by the cams D^3 and D^4 , as before described. The raising of the cylinder B through the instrumentality of the levers j^{10} releases the rollers j' from the sheet, a part of which sheet still remains upon the cylinder B , thus allowing the grippers of the cylinder B' to draw the sheet

unobstructed entirely from the surface of the cylinder B and down the fingers f' . The crank G continuing its rotation back to its starting-point, the cylinder B' , now down, prints the second side of the sheet and continues to rotate sufficiently more than one complete revolution to bring the tail m of the sheet above the points of the fingers f , the tail end, m , of the sheet in the meanwhile resting upon the sheet-supporting fingers o^4 until the cylinder B' commences to perform its retrograde rotation to the position required to take another sheet. At this time, through its connections already described, the cam F has just brought the fly-fingers f to rest upon the rod f^3 , the form of said cam being such as to retain them there until (another revolution of the crank G commencing) the sheet has been passed tail first down the fingers f , by said retrogression of the cylinder B' , to the stop f^5 , at which time the cam F , through its connections, causes the fly-fingers f to describe an arc over to the fly-board C' , Fig. 1, delivering the sheet thereon, and then again returning it at the proper time to the stop-rod f^3 to receive the succeeding sheet.

The arrangement and operation of the equilibrating weights has been sufficiently explained in the description of the weights themselves and their connections already given.

In the arrangement of press illustrated in Figs. 10, 11, 12, and 13, and hereinbefore fully described, for printing from a continuous web or roll of paper and delivering to a folder attachment, the operations of the press proper are the same as those just described therefor. By the additional attachments, however, as has been explained in detail, the sheets are automatically cut from the web and automatically fed to the grippers of the cylinder B ; but the fly-fingers f , with their folding-blade f^4 , perform a shorter arc of vibration in delivering the sheets to the vertical folding-rollers h^6 than if delivering flat upon a fly-board, the cam F being of course properly proportioned, formed, and adjusted to impart the necessary throw of the fly in either case. It is obvious, therefore, that these presses may be arranged to print either from the continuous web and deliver flat upon a fly-board, or from sheets separately fed from a feed-board and delivered to a folder, by simply a suitable attachment of such proper parts therefor as have been herein described.

By means of the above-described system and arrangement of parts there is produced at comparatively small cost a machine capable of rapidly printing newspapers or other work on both sides, fed either from separate sheets or from a continuous web, and delivered either flat or to a folder, the work being printed from the original type-form without the expense of or time consumed in stereotyping the forms and preparing the stereotype-plates for the press.

I do not confine myself to the methods described for imparting motion to the fly-fingers,

nor for raising and lowering the impression-cylinders, nor for actuating the vertical folding-rollers, as all of these desired motions or movements may be effected in many well-known ways; but,

As of my invention, I claim—

1. In a perfecting printing-press, in combination with one reciprocating type-bed carrying two forms, two impression-cylinders geared to and continuously rotated in opposite directions by said bed, and arranged, substantially as described, so that one cylinder takes the sheet at or near its top when practically at rest for printing the first side of the sheet, and the other cylinder takes the sheet at or near its bottom when practically at rest, as delivered from the top of the first cylinder, for printing the second side of the sheet, substantially as and for the purposes set forth.
2. In a perfecting printing-press, in combination with one reciprocating type-bed carrying two forms, two impression-cylinders and two sets or series of fingers or strippers, all arranged and operating, substantially as described, so that one cylinder delivers each sheet head first from its upper side to and upon one set of said fingers or strippers inclined to the lower side of the other or second cylinder, whence the sheet is taken by the second cylinder and delivered tail first upon the second set of fingers or strippers, substantially as and for the purposes set forth.
3. In a perfecting printing-press, in combination with one reciprocating type-bed carrying two forms, one or more reciprocating weights provided with a rack or racks, and

one or more gear-wheels running upon a stationary stud or studs and geared intermediately to said rack, and a rack or racks attached to the type-bed, said weights being so proportioned as to equilibrate the momenta of the reciprocating bed and attached parts, substantially as set forth.

4. In a perfecting printing-press constructed to print from two forms upon a reciprocating type-bed, in combination with two impression-cylinders continuously geared to and rotated by said bed, an automatic feeding and sheet-cutting apparatus, consisting of sheet-cutting cylinders d^{11} and d^{15} , the pressure or feeding roller p^6 , the strippers or fingers d^{14} , the tape-rollers j^7 and j^9 , their tapes b^2 , and the lifting pressure or feed rollers j^5 , whereby paper in the roll is automatically fed in the machine, cut into sheets, and said sheets fed by the first-impression cylinder, substantially as set forth.

5. In a cylinder printing-press, in combination with cylinder-grippers provided with cam-shaped hubs, sheet-lifter fingers consisting of thin slotted blades resting upon said hubs, whereby the sheet is gripped between the upper face of the sheet-lifter fingers and the lower face of the grippers and the edge of the sheet lifted from the cylinder's surface by the operation of the grippers, substantially as and for the purposes set forth.

JOHN T. HAWKINS.
